TOY CONSTRUCTION

Robert B. Bennett, Detroit, Mich.

Application September 14, 1944, Serial No. 554,060

6 Claims. (Cl. 280—30)

1

This invention relates to toy vehicle construction, and more particularly to a combination rolling and rocking vehicle furnishing amusement, exercise and transportation for children or adults.

It is the object of this invention to provide a toy construction embodying a rolling and rocking vehicle characterized by a high degree of safety for the rider.

It is the further object herein to provide a toy construction with means employed for eliminating or minimizing damage to furniture or wood work.

It is the still further object to provide a sturdy rocking and rolling toy characterized by simplicity of construction and low cost of manufacture.

Other objects will appear in the following specification and claims which set out the various elements of the invention and their combinations as illustrated in the accompanying drawings of which—

Fig. 1 is a top plan view of the rolling toy.

Fig. 2 is a side elevational view thereof, and

Fig. 3 is a side elevational view of the rolling toy inverted as a rocker.

It will be understood that the above figures are merely illustrations of a preferable embodiment of the invention and that other embodiments are contemplated within the scope of the invention as set out in the appended claims.

In the drawing, Figs. 1 and 2, the rolling vehicle consists of parallel spaced arcuately formed members 11 and 12 preferably joined at their opposite ends by transverse bumper cross members 13 and 14.

Members 11 and 12 forming the sides of the rolling toy are maintained rigidly by the intermediate cross bars 15, 16, 17 and 18, upon 15 and 18 of which is provisioned and secured longitudinally disposed seat 19. Said seat may be narrow, as shown, throughout its length or on the other hand may be very wide fully covering the rear space between members 11 and 12 and being cut narrow at its forward part to accommodate the legs of the rider.

As shown in Fig. 2 a slightly inclined back 20 is provided for seat 19, which extends therefrom and is suitably secured to cross bar 16.

Angular front wheel supporting and steering shaft 21 is rotatably provisioned and supported centrally by thrust bearing 22 carried by seat 19. Collar bearing 23 secured to cross bar 17 provides an upper journal for steering post 21, upon the upper end of which is provisioned steering wheel 24.

2

Drive wheel 25 rotatably journaled at the bottom end of steering post 21 has secured thereto cross shaft 26, upon opposite ends of which are provisioned wheel rotating foot pedals 27 and 28.

It is contemplated that said pedals may be omitted with wheel 25 being rotatable relative to cross shaft 26 which would act merely as a foot rest.

While wheel 25 is adapted as a central front support for the toy, a pair of spaced smaller wheels 29 and 30 are journaled and retained preferably on stud shafts 31 and 32 extending from the inner ends of parallel members 11 and 12 respectively. A tricycle gear is thus provided for the rolling toy. On the other hand wheels 29 and 30 may be journaled from a single transverse shaft.

Protruding or extending end members 13 and 14 provide bumpers adapted to minimize or eliminate damage to the wood work or furniture when the toy is operated carelessly. It is noted also that the lower edges of members 13 and 14 are very near the floor making it impossible for the toy to run over anything or hurt another child. Obstacles are thus pushed out of the way, instead of being run over, as might be the case with the conventional tricycle.

Referring to Fig. 3 the rolling toy is shown inverted to be used as a rocking toy. A pair of spaced parallel braces 33 and 34 interconnect the ends of arcuate members 11 and 12 respectively, being suitably secured by screws 35 or by bolts or even welds, if desired. Members 33 and 34 thus provide guards for the rider. The sides may be fully enclosed by members 36, fragmentarily shown in Fig. 3, interposed between guards 33 and 34 and rocker members 11 and 12 respectively, secured by suitable screws 37, or bolts or welds, if desired.

It is contemplated, however, that side members 36 may be eliminated if desired; though a greater degree of safety is attained when these members are used, particularly for small children.

Seat member 19 inverted in Fig. 3 is also the seat for the rocking toy as shown in Fig. 3. Flat member 38 resting on seat 19 and angularly inclined and secured against cross bar 15 and end member 13 provides a back rest. On the other hand it may be desired to have a more central back rest 39 resting on seat 19 and with the top portions of its sides suitably secured at 40' to the spaced guard members 33 and 34.

Referring to Figs. 1 and 3 arcuate inwardly projecting foot guard members 40 are employed secured at 41 upon cross bars 16 and 17 adjacent

rocker members 11 and 12. Guards 40 form foot rests and prevent the child's feet from being crushed or hurt by accidentally slipping under rockers 11 or 12.

A further safety feature resides in the portions 42 and 43 forming part of seat 19, which extend beyond the edges of rockers 11 and 12. Projecting members 42 and 43 as well as the cross members 13 and 14, limit the degree of rocking movement making it practically impossible to rock the 10 toy too far.

The rocking and rolling toy may be made of any suitable material such as metal, plastics, or wood. The various members, i. e., rockers 11 and 12 and cross bars 15, 16, 17 and 18 may be in any 15 desired form, such as rod, tubing, channel or angle members.

It will be noted that bumper members 13 and 14 make it practically impossible to upset the toy when used as a rolling toy, said bracing members extending the full width of the toy would stop any upsetting movement immediately upon either engaging the floor or other riding surface.

Bumpers 13 and 14, which may be omitted for convenience, are formed arcuately at their ends to join rockers 11 and 12 eliminating sharp corners which could injure a person. The lack of any sharp protruding angles in the toy thus provides an additional safety feature.

Having described my invention, reference 30 should now be had to the claims which follow for determining the scope thereof.

I claim:

1. A rolling and rocking toy comprising a pair of spaced arcuate side members with their central portions extending upwardly, spaced reinforcing bumper members secured to the opposite ends of said arcuate members, a seat supported between said side members, a central steering and supporting front wheel extending from one end of said seat, and a pair of spaced rear wheels journaled by and extending from the ends of said arcuate members, said side members being upsettable 180° to provide a central rocking support.

2. A rolling and rocking toy comprising a pair 45 of spaced arcuate side members with their central portions extending upwardly, spaced reinforcing bumper members secured to the opposite ends of said arcuate members, a plurality of spaced cross bars interposed between said side members, a seat supported between said side members, a central steering and supporting front wheel extending from one end of said seat, and a pair of spaced rear wheels journaled by and extending from the ends of said arcuate members, 50 said side members being upsettable 180° to provide a central rocking support.

3. A rolling and rocking toy comprising a pair of spaced arcuate side members with their central portions extending upwardly, spaced reinforcing bumper members secured to the opposite ends of 55

said arcuate members, a plurality of spaced cross bars interposed between said side members, a seat supported between said side members, a central steering and supporting front wheel extending from one end of said seat, and a pair of spaced rear wheels journaled by and extending from the ends of said arcuate members, said side members being upsettable 180° to provide a central rocking support, the ends of said seat member extending outside said arcuate members for limiting rocking movements.

4. A rolling and rocking toy comprising a pair of spaced arcuate side members with their central portions extending upwardly, spaced reinforcing bumper members secured to the opposite ends of said arcuate members, a plurality of spaced cross bars interposed between said members, a seat supported between said side members, a tricycle rolling gear extending below the ends 20 of said arcuate members, side bars extending between the ends of each arcuate member, and side wall members interposed between said arcuate members and said side bars.

5. A rolling and rocking toy comprising a pair 25 of spaced arcuate side members with their central portions extending upwardly, a seat supported between said side members, a central steering wheel extending from one end of said seat, and a pair of spaced rear wheels journaled by and extending from the ends of said arcuate members, said toy being rotatable 180° whereby said side members provide a central rocking support.

6. A rolling and rocking toy comprising a pair 35 of spaced arcuate side members with their central portions extending upwardly, a seat supported between said side members, a central steering and supporting front wheel extending from one end of said seat, and a pair of spaced rear wheels journaled by and extending from the ends of said 40 arcuate members, said side members being upsettable 180° to provide a central rocking support, the ends of said seat member extending outside said arcuate members for limiting rocking movements.

ROBERT B. BENNETT.
